DOUGH FORMER

Sylvester Patt, Willoughby, Ohio

Application March 25, 1940, Serial No. 325,895

1 Claim. (Cl. 303—24)

This invention relates to improvements in dough-forming machines and particularly to novel means for mounting rotating rollers, cutter blades and the like of a dough-forming machine in supporting standards.

It is an object of this invention to provide novel means for mounting rollers, cutters and the like of a dough-forming machine in the machine frame whereby speedy and expeditious removal of the rollers for purposes of cleaning or adjustment is permitted.

Another object of the present invention is to provide novel bearing assemblies for the rollers or the like of a dough-forming machine which not only permit speedy removal upon occasion but which assure proper alignment of the rollers when held in the frame. This is of importance inasmuch as the rollers in machines of this nature are disposed in spaced parallelism and the adjustment of distance between the axis of rotation must be maintained without variation if uniformity of product is to be maintained.

An important advantage of the novel bearing assemblies according to the present invention, especially suiting the same to use in the mounting of rollers or the like in a dough-forming machine, is that in the parts of the assemblies permanently associated with the rollers or the like there are no moving parts or inaccessible concavities which would make difficult the cleaning of the device in accordance with established custom.

Noteworthy among the features of the novel dough former according to the present invention are its simplicity and ruggedness of construction, the former suiting the device to the requirements of manufacture under conditions of mass production and the latter assuring long useful life.

Other objects, advantages and features of the new and improved dough former according to the present invention will be apparent to those skilled in this art during the course of the following description.

Regarded in certain of its broader aspects the improved mounting means according to the present invention for holding trunnions of rollers and the like in open slot-like formations in the form of a dough forming machine comprises flanged sleeves, freely rotatably receivable on the trunnions, having openings formed in peripheral parts of the flanges, the sleeves having an external size permitting fitting into the slot-like formations of the frame; and spring-urged sliding latch members mounted in the frame, adapted

to engage with the peripheral openings in the sleeve flanges whereby the sleeves can be removable held within the formations in the frame.

In order to facilitate a fuller and more complete understanding of the present invention a specific embodiment thereof herein illustrated will be hereinafter described, it being clearly understood, however, that the illustrated embodiment, although presently preferred, is provided solely by way of example of the practice of this invention and not by way of limitation thereof except insofar as the invention is recited in the subjoined claim.

Referring then to the drawings,

Fig. 1 is substantially a front elevational view of the presently preferred embodiment of this invention.

Fig. 2 is essentially a rear elevational view of the device illustrated in Fig. 1 with parts of the base and one of the standards broken away.

Fig. 3 is essentially an end elevational view of the device with the operating handle shown in phantom.

Fig. 4 is an elevational view of the opposite end of the device with parts of the standard and base broken away.

Fig. 5 is essentially a vertical sectional view of Fig. 1 taken along the line 5—5 thereof.

Fig. 6 is substantially a top plan view of the device illustrated in the foregoing figures.

Fig. 7 is essentially a vertical sectional view of Fig. 6 taken along the line 7—7 thereof; and

Fig. 8 is a front elevational view of a portion of one of the cutter rollers.

In the illustrated presently preferred embodiment of this invention generally designated by the reference character 10 a base 11 is provided upon which are rigidly mounted spaced essentially parallel upright standards 12 in upper parts of which is mounted a horizontally extending freely rotatable feed roller 13 substantially cylindrical in shape and having trunnions 14 which are received in openings formed in the standards. A handle 15 mounted by means of a set screw 15a upon one of the trunnions 14 is provided to facilitate manual rotation of the roller 13. The U-shaped frame element generally designated by the reference character 16 comprising a cross piece 16a and integrally formed arms 16b is swingably mounted upon upper parts of the standards 12 by appropriate fastening means such as the screws 16c. The cross piece 16a of the frame 16 is adapted to overlie the roller 13 hereinabove described and the arms 16b are provided with aligned cut-away formations to re-

ceive trunnions 17a of a former roll 17 which rests upon yielding intrinsically resilient supporting members 18 mounted upon parts of the standards 12. The former roll 17 is substantially cylindrical in shape and is provided with spaced V-shaped cutters 17b which, when dough is passed through the machine upon the feeder roll 13, form the dough into continuous strips as will be obvious to those skilled in this art. It is to be noted that the axis of rotation of the rollers 13 and 17 are substantially parallel and are adjustable with respect to each other by means of a screw 19 mounted in a U-shaped frame 20 pivoted to parts of the standards 12 by pins 20a. As will be obvious from the drawings the screw 19 bears against a part 16a of the U-shaped member 16 whereby the roller 17 can be pressed against the roller 13 despite the upwardly directed force of the resilient members 18. In order that the rollers 13 and 17 may rotate at the same speed, gears 21 and 22 are mounted upon the trunnions 14 and 14a respectively. A doctor blade 23 mounted upon a cross bar 24 cooperates with the feed roller 13 to remove material clinging to the surface thereof as will hereinafter be described.

Aligned obliquely disposed open slot-like formations 25 in upper parts of the standards 12 serve to receive sleeves 26 having integrally formed radially extending flanges 27 within which is freely rotatably received a shaft 28 of a transverse cutter assembly generally designated by the reference character 29. The shaft 28 carries rollers 30 rigidly attached thereto by pins 31 having radially extending fins 30a upon which are mounted horizontally disposed blades 32 attached thereto by appropriate fastening means such as screws 32a, the blades being adjusted preferably to pass substantially near the feed roller 13 during rotation of the shaft 28. A gear 33 rigidly mounted upon the shaft 28 meshes with a similar gear 34 rigidly mounted upon the trunnion 14 whereby rotation of the trunnion 14 results in rotation of the shaft 28 and the cutter blades 32 in addition to rotation of the former roller 17 as hereinabove described.

Pins 35 freely slidingly received in openings 36 formed in parts of the standards 12 are urged toward the flanges 27 carried on the sleeves 26 by springs 37 sleeved upon diminished portions 35a of the pins substantially as shown. End portions 35b of the pins 35 project outwardly from the surface of the standards 12 and are received in registering openings formed in the

flanges 27 whereby the sleeves 26 are retained within the slot-like formations 25 in the manner illustrated in the figures of the drawings. To facilitate manual sliding motion of the pins 35, handles 38 are provided, the handles also serving to prevent the pins from moving to an undesired degree under action of the springs 37. For facilitating sliding of the pins 35 against the action of the springs 37, cams 39 are provided upon side parts of the frame 12 against which the handles may ride when the pins are swung about their axis.

Having described the structural features of the presently preferred embodiment of this invention the mode of operation thereof will next be described although it is believed that the operation of the device will be substantially apparent from the foregoing description. Dough is fed between the rotating rollers 13 and 17 whereby the V-shaped formation 17b on the surface of the roller 17 serves to press the dough into a continuous sheet having longitudinal furrows formed in the top surface thereof. It will be recalled that rotation of the feed roller 13 produces concomitant rotation of the former roller 17 and also of the shaft 28 carrying the cutter blades 32. As the blades move against the roller 13, the furrowed dough is transversely cut and the cut product is removed from the roll 13 by the doctor blade 23.

It is to be understood that this invention is capable of extended application and is not confined to the precise illustrated forms nor described construction and, therefore, such changes and modifications may be made therein as do not affect the spirit of the invention nor exceed the scope of the appended claim.

Having thus described the present invention, what it is desired to secure by Letters Patent is:

Improved mounting means for holding trunnions of rollers and the like in open slot-like formations in the frame of a dough forming machine comprising flanged sleeves, freely rotatably receivable on the trunnions, having openings formed in peripheral parts of the flanges, the sleeves having an external size permitting fitting into the slot-like formations of the frame; and spring-urged sliding latch members mounted in the frame, adapted to engage with the peripheral openings in the sleeve flanges whereby the sleeves can be removably held within the formations in the frame.
